UNITED STATES PATENT OFFICE.

JOHN S. DAVIS, OF TOLEDO, OHIO, ASSIGNOR TO THE TOLEDO MOWER
AND REAPER COMPANY, OF SAME PLACE.

GRAIN-CARRIER.

SPECIFICATION forming part of Letters Patent No. 252,081, dated January 10, 1882.

Application filed October 13, 1881. (No model.)

To all whom it may concern:

Be it known that I, JOHN S. DAVIS, of Toledo, in the county of Lucas and State of Ohio, have invented certain new and useful 5 Improvements in Grain-Carriers, of which the following is a specification.

My invention relates to improvements in grain-carriers of the class composed of endless aprons, belts, or chains, and chiefly employed, 10 in connection with grain-binding machines, to deliver the grain as cut from the harvester-platform to the binding mechanism, my improvements particularly pertaining to that 15 use of such class of grain-carriers in which provision is made for tightening and loosening the aprons, belts, or chains.

My objects, mainly, are to provide simple and readily-operated mechanism by which the canvas or other endless carrier may be held under suitable tension and be tightened or slackened by adjustment of its supporting-rollers relatively to each other. Another object of my invention is to provide for the automatic or self adjustment of the carrier in 25 such manner that tension may be equalized upon the front and rear edges of the apron, or the front or rear belts or chains of a series, thereby avoiding the imperfect working of carriers, commonly resulting from unequal stretching or shrinking of different parts.

My improvements consist in a novel organization of mechanism and in certain combinations of devices, hereinafter to be specifically claimed, after describing my invention, in connection with the accompanying drawings, 35 which show mechanism suitably organized in accordance with my invention and adapted to a harvester-platform. Essential features of my improvements may be employed in connection with elevating-aprons or inclined carriers—such, for instance, as used for conveying grain from the inner ends of platforms to receivers or binding-receptacles—and the details of construction and arrangement of parts 40 may be varied to suit the varying circumstances under which the carrier is to be worked.

Figure 1 is a plan view, showing portions of the cutting apparatus, the platform, a one-piece-canvas carrier, and its supporting and 45 adjusting mechanism, the carrier being partly

broken away. Fig. 2 is a view, partly in elevation and partly in transverse vertical section, on the line 2 2 of Fig. 1, showing the outer and adjustable roller for supporting the carrier and the manner of supporting it. Fig. 55 3 is a plan view of the devices for supporting the roller, and by means of which the roller is adjusted. Fig. 4 is a view of the roller-supporting devices, partly in elevation and partly in section, on the line 4 4 of Fig. 3. Fig. 60 5 is a view, partly in rear elevation and partly in section, showing the carrier-adjusting lever and detent at the rear of the platform.

An endless carrier, A, shown in this instance as formed of one piece of canvas, is mounted upon rollers B B', crossing the platform at its inner and outer ends. The roller B may be driven in any suitable way, as by gearing actuating the pinion B², and, as shown, is mounted in fixedly-secured front and rear bracket-bearings, a a', respectively, attached to the finger-beam C, and to a back board or rear frame-piece, C', of a harvester-platform of suitable construction, and constituting the carrier-frame. The roller B' is adjustable in the carrier-frame 70 toward and away from the fixedly-supported roller B, and is free to oscillate slightly, as will farther on be understood. The means in this instance employed for supporting and adjusting the roller B', and for securing it in the 75 adjusted position, are as follows: A bar, D, secured at its ends, crosses from front to rear of the platform, between the upper and lower portions of the carrier. Brackets d d', secured to the finger-beam and to the back board of 80 the platform, and bolts, serve to firmly secure the cross bar in place without interfering with the carrier or apron. A lever, E, is jointed at its inner end to an arm, e, firmly fastened to the cross-bar and projecting toward the roller 85 B'. The lever is fitted in a mortise or slot in the cross-bar arm, extends rearwardly between the top and bottom portions of the carrier, and is provided with a handle, E', projecting out 90 through a longitudinal slot in the rear frame-piece or back board, C', of the platform. A ratchet-rack or serrated stop-plate, F, is provided at the lower edge of the stop c of the back board, and a tooth or detent, f, on the hand-lever engages this rack to hold the lever 95 100

in its adjusted position. The ordinary spring-detent may be employed; but, as shown, the detent is firmly fastened to the adjusting-lever, and the lever is made sufficiently yielding to enable the operator to spring it, and so disengage the detent and stop for adjustment of the parts. The lever has connection with the cross bar D, intermediate the ends of this bar, preferably somewhat nearer the front than the rear edge of the platform, as shown, so that the lever may be connected at a point about midway the width of the platform with the adjustable supporting mechanism of the roller B'. The lever connects with an adjustable supporting-bar, H, for the roller B' by means of a link or connecting-rod, G. This link is pin-jointed at one end between fixedly-attached clips or lugs on the lever, and near its fulcrum, between which lugs the link loosely fits, with its rounded end bearing in a correspondingly-shaped recess formed in the lever. In this way unnecessary thrusting strain upon the lugs g (only the top one of which is shown) and the pivot g' is avoided. The opposite end of the connecting-rod or link G is pin-jointed at h to the bar H, to which it is fitted, either by means of lugs, such as those on the lever, or by means of a rounded recess midway the length of this bar.

30 The supporting-bar H, like the cross-bar D and operating-lever E, is arranged between the top and bottom portions of the canvas A, and between the two rollers, and is pivoted at its ends to cross-heads or sliders I I, having boxes or bearings for the roller B'. The bar H, the cross-heads, the pivots i i, connecting the bar with the cross-heads, the bearings or sockets J J in the cross-heads, and suitable guideways for the cross-heads make up the adjustable supporting mechanism for the roller B', which mechanism is controlled and secured by means of the adjusting-lever and its rod or link G. The roller B' is journaled at its ends in the cross-head bearings J J, and the cross-heads are supported and guided in their reciprocations between strips or bars K K K' K', the front guideway-bars, K K, being secured to the back of the finger-beam C and to the bottom of the platform by screws, and the guideway for the rear cross-head being bolted to the platform back board, C'. A metallic bar or strap, l, is bolted to the platform-bottom, (see Figs. 1 and 2,) and is also secured to the finger-beam and back board by bolts, thus securely uniting the parts. Flanges b b and b' b', upon the ends of the rollers B and B', prevent displacement of the carrier, as usual. I prefer to form these flanges with the journals of the rollers, as clearly shown in Fig. 2.

60 From the above description it will be understood that the bar H maintains the parallelism of position of the roller-carrying cross-heads throughout their adjustments, and that by means of the lever, the link, and the detent the movable carrier-supporting roller may be suitably adjusted and secured in the carrier-frame

to properly stretch the canvas or to relieve it of too great tension, as well as to leave it slack when not in use, thus rendering unnecessary the employment of straps and buckles or other similar devices commonly used for lengthening, shortening, and slackening or unfastening carriers. It will further be obvious that an injurious unequal stretching of either edge of the canvas—the front or back portions of the carriers—will be prevented, when the rollers are properly adjusted relatively to each other, by the horizontal oscillation or vibration about the pivot h of the supports of the roller B'. The slight vibratory movement allowed the roller-supports about the pivot h, connecting the bar H and link G, is amply sufficient to prevent the unequal strains which would otherwise occasionally be brought to bear upon the front and back portions of the carrier—such, for instance, as caused by the temporary passage or collection of stalks of grain, &c., between the carrier and its rollers. At such times the movement toward the roller B of that end of the roller B' around which the unusually strained portion of the carrier passes would obviously cause the movement of the opposite end of the roller B' away from the roller B, thus dividing or equalizing the strain. By making the bar H resili- 95 ent or self-yielding, as presently to be explained, and keeping it under proper strain, but little, if any, perceptible unusual tension would be exerted upon the canvas during such oscillation of the roller, as the bar would adjust itself to compensate the increased strain on the carrier.

To prevent cramping and enable the roller B' freely to assume the slightly diagonal position it occupies when vibrated, the roller-journals are fitted loosely in the bearings J J of the cross-heads. As these journals are quite short, and as such journals and bearings would not ordinarily be closely fitted, no particular care is necessary in mounting the roller in its bearings to allow for the very slight amount of vibration needed. If preferred, however, oscillating boxes for the roller-journals may be provided in the cross-heads.

To provide for automatic movement or self-adjustment of the roller B' toward or away from the roller B, and so compensate for slight variations in the length of the carrier without resort to the lever for positively adjusting the position of the roller B', the bar D or the bar H, or both of them, are made to possess a proper degree of resiliency, and either or both these bars may be made sufficiently yielding of wood, steel, &c. The bars are preferably both made of wood, and one or both of them may be reduced in size at and near its center to give increased elasticity. The dotted lines, Fig. 4, represent the bar H as cut away to give it proper resiliency. By the spring-pressure of this bar the roller B' is rendered self-adjusting to a limited but sufficient extent under ordinary circumstances. The spring-bar H being normally strained or slightly bowed by the

thrust of the lever-controlled link G, is in this way obviously given the capacity of acting properly to accommodate slight variations in the length of the carrier, the bar being brought 5 under increased strain by the contraction of the carrier and consequent automatic movement of the roller B' toward the roller B, and being partially relieved of strain by the lengthening of the carrier, when the pressure of the 10 bar automatically moves the cross-heads and the movable roller away from the fixed roller.

In connection with carriers composed of a series of belts, chains, or toothed bands, the lever-supporting cross-bar D may be dispensed 15 with and its equivalent, consisting of a suitable post or stand secured to the bottom of the carrier-frame or platform and projecting up between the lower portions of two of the bands, be employed. The top of said post would serve 20 as a support for the lever, which could thus be jointed to the post-top instead of to the arm e, so as to vibrate between the upper and lower sections of the belts and operate the bar H and its connections by way of the link G, as 25 before explained. I prefer, however, to use the cross-bar D in all cases.

I do not broadly claim adjustably-supporting rollers for endless grain-carriers or aprons, nor, broadly, the employment of sliding boxes 30 for adjusting such rollers, as I am aware that prior to my invention various devices have been devised for adjusting the rollers of grain-carriers.

I disclaim the combination, broadly considered, of an endless carrier for a harvester, supporting-rollers for the carrier located at the ends of the carrier-frame, and automatically-yielding mechanism placed between said rollers and between the upper and lower portions 40 or opposite surfaces of the carrier to vary the distance between the rollers, as I am not the first inventor thereof.

I claim as of my own invention—

1. The combination of an endless carrier for 45 a harvester, the supporting-rollers for the carrier, located at the ends of the carrier-frame, the adjustable supporting mechanism between said rollers, and between the upper and lower portions or opposite surfaces of the carrier, and

means for positively adjusting and securing 50 said mechanism, substantially as and for the purpose hereinbefore set forth.

2. The combination of the cross-heads provided with bearings, the carrier-supporting roller mounted in said bearings, the guideways 55 for the cross-heads, and the adjustable bar connecting the cross-heads, substantially as and for the purpose hereinbefore set forth.

3. The combination of the carrier, its supporting-rollers, the sliding boxes or cross-heads 60 provided with bearings for one of said rollers, the cross-bar between the upper and lower portions of the carrier, with which bar the cross-heads are jointed, and the adjusting-lever linked to said bar, substantially as and for the 65 purpose hereinbefore set forth.

4. The combination, substantially as hereinbefore set forth, of the adjustable carrier-supporting roller, the sliding boxes, the guideways, the resilient bar having jointed connection 70 at its ends with said sliding boxes, the adjusting-lever, the link or connecting-bar, and means for securing the lever in its adjusted position.

5. The combination of the platform, the carrier, the roller mounted in fixed bearings, the adjustable roller, the cross-heads provided with bearings for said adjustable roller, the bar connecting said cross-heads, the link-rod, the lever, and the cross-bar with which said lever 80 has pivotal connection, these members being and operating substantially as hereinbefore set forth.

6. The combination of the platform, the adjustable carrier-supporting roller, the adjusting and supporting mechanism therefor, the slotted back board, and the rack with which the detent of the adjusting-lever engages, substantially as and for the purpose hereinbefore set forth.

In testimony whereof I have hereunto subscribed my name this 10th day of October, A. D. 1881.

JOHN S. DAVIS.

Corrections in Letters Patent No. 252,081.

It is hereby certified that in Letters Patent No. 252,081, granted January 10, 1882, upon the application of John S. Davis, of Toledo, Ohio, for an improvement in "Grain Carriers," the word "slot," in line 98, on page 1 of the printed specification attached to and forming a part of said Letters Patent, was erroneously printed "stop;" that the proper corrections have been made in the files and records of the Patent Office, and are hereby made in said Letters Patent.

Signed, countersigned, and sealed this 17th day of January, A. D. 1882.

[SEAL.]

A. BELL.

Acting Secretary of the Interior.
